CLAIM

The ornamental design for a booster for detonating bulk explosives, as shown and described.

DESCRIPTION

FIG. 1 is a front and right side perspective view of a booster for detonating bulk explosives, with a cap thereof exploded from the remainder of the booster for detonating bulk explosives;

FIG. 2 is a front and right side perspective view of the booster for detonating bulk explosives;

FIG. 3 is a bottom and left side perspective view of the booster for detonating bulk explosives;

FIG. 4 is a front elevation view of the booster for detonating bulk explosives;

FIG. 5 is a rear elevation view of the booster for detonating bulk explosives;

FIG. 6 is a top plan view of the booster for detonating bulk explosives;

FIG. 7 is a bottom plan view of the booster for detonating bulk explosives;

FIG. 8 is a right side elevation view of the booster for detonating bulk explosives; and,

FIG. 9 is a left side elevation view of the booster for detonating bulk explosives.

The broken lines in FIGS. 1-9 and the unshaded areas adjacent them depict portions of the booster for detonating bulk explosives that form no part of the claimed design.

1 Claim, 8 Drawing Sheets
